No. 8,438.

PATENTED OCT. 14, 1851.

J. YANDELL.
INSULATOR FOR TELEGRAPHS.

UNITED STATES PATENT OFFICE.

JOHN YANDELL, OF ST. LOUIS, MISSOURI.

IMPROVEMENT IN INSULATORS FOR TELEGRAPHS.

Specification forming part of Letters Patent No. **8,438**, dated October 14, 1851.

To all whom it may concern:

Be it known that I, JOHN YANDELL, of St. Louis city and county, and State of Missouri, have invented a new and useful Improvement in the Mode of Insulating the Wires of Magnetic Telegraphs and other Magnetic Apparatus, which is described as follows, reference being had to the annexed drawings of the same, making part of this specification.

Figure 1 is an elevation of the upper end of a telegraph-pole with the insulator inserted therein. Fig. 2 is a vertical section through the center of the same. Fig. 3 is a side view of a bracket containing an insulator designed to be used in securing to a tree, when that mode of support is employed. Fig. 4 is a section through the same at the line *x x* of Fig. 3. Fig. 5 is a front view of the same. Fig. 6 is a side view of the insulator. Fig. 7 is a longitudinal section of the same. Fig. 8 is an end view of the same. Fig. 9 is a cross-section of the same. Fig. 10 is an end view of a modification of the same when used to receive the wire from the top of the post. Fig. 11 is a longitudinal section of a modified form of the same, the flange being concentric with the cylindrical portion forming the body. Fig. 12 is a sectional view of a post with the insulator, Fig. 11, inserted, this form being used when the post is not large enough at the top to work into the shape of Figs. 1 and 2.

The nature of this invention consists in cutting the sides of telegraph-posts near their upper ends, and the sides of the brackets, when it is designed to use trees as a means of support for the wires, so as to form depressions on either side about one-third the thickness of the post or bracket in depth, and boring a hole having an eccentric recess at one end through from one depression to the other, and inserting in said hole a glass cylindrical insulator, in which the wire is introduced through a slot in its upper part, having an eccentric or concentric flange at one end, and corresponding in size and form with the hole and recess, and held in its place by a cleat in such a manner as to afford an insulator which shall be prevented from turning within the post and bracket, to prevent the escape of the wire from the same, and be protected from rain and sleet, &c., during stormy weather.

To enable others skilled in the art to make and use my invention, I will proceed to give a more particular description of its construction.

A is the upper portion of the telegraph-post hewed to an edge at its upper end, so as to shed off rain, snow, sleet, &c., and having a horizontal hole bored through it a short distance below its upper end, and depressions hewed in its sides below said hole, to prepare it for the reception of the insulator. This is done in the following manner: A hole—say, two and one-quarter inches in diameter—is first bored, by an auger, in the post, about one-third its diameter in depth, and another auger of less size—say one and three-quarter inch—is then inserted in this hole, and another hole of this size is bored through the remainder of the post and parallel with the first and concentric with the same, one side of which (being its upper part when the posts are placed upright) is on a line with one side of the first-mentioned hole. This being done, an inclined slit, B, sufficient to admit the wire, is sawed from one side of the post into the holes. When the top of the post is too small to permit the usual projection of the wood over the insulator the slit must be from above, so as not to weaken the post too much. Any suitable cover may be placed over to shed the water, &c. The sides of the post at the ends of the holes, on the opposite side of said holes, are then sawed, as at C, so as to incline at a reverse angle with the slit B. The sides of the post are then hewed from below, and the body of timber to the depths of the curfs last sawed removed, so as to form depressions on either side of the post below the hole, straight at their upper parts, the face of one being within about three-eighths of an inch of the bottom of the larger hole first bored, so as to leave a recess, D, at one end of the smaller hole, extending through the post, eccentric with the same. The corners of the depressions next the hole are then cut off with a chisel, as at E, to prevent the possibility of the wires when set being blown in contact with them. The post is then ready to receive the insulator.

F is the glass insulator, made in the form of a cylinder, corresponding with the size of the hole through the post, with its interior bore, which is flared outward or enlarged at

the ends, and eccentric or concentric with the outer periphery. When eccentric the heaviest part is opposite to the slit from end to end.

G is a slit to allow the entrance of the wire into the bore.

The eccentric flange H attaches to one end of the insulator, its upper part or edge terminating at the top of the cylinder, and its lower edge extending some distance below the bottom of the same, so as to fit within the recess D, formed by the hole first bored in the post. The insulator is then inserted in the hole (the wire being passed through the slit in the cylinder to the bore of the same) and the flange at the end is fitted into the recess D, which, being eccentric with the cylinder, prevents the insulator turning either way.

I is a wooden oblong cleat made concave and beveled at its upper end and nailed to the even surface of one of the depressions with its upper end resting against the end of the insulator. This prevents its being drawn out of the hole by the movements of the wire or other causes.

K is a wooden bracket designed to be nailed to a tree, when this manner of support for the wires is used, or to the sides of the telegraph posts the required distance below the upper insulator, when two wires are used. It is curved on its under and upper parts, and bored in a similar manner to the posts, so as to form a similar opening for the insulator, and is provided with an inclined or vertical slit, L, extending from its outer part into the insulator-hole, and is sawed and hewed on both sides below the hole the same depth as the depressions in the sides of the post, so as to cause its upper part to overhang the ends of the insulator, (which is inserted and secured in the hole in the same manner that the insulator of the post is inserted and secured in its opening,) and forms a roof for the protection of the same from rain, &c.

M is a modification of the insulator, made similar to the one first described, except that its flange is concentric with the cylinder, in-

stead of eccentric, and that it is provided with a notch in the flange, through which a nail, N, is driven into the post or bracket, whose head prevents it from either turning or becoming dislodged from its place.

O is a modification of the first described, except that the flange is sometimes omitted when peculiar conditions in the shape of the top of the pole may render it necessary to reduce the bore as much as possible to retain strength in the pole.

P is a view of the head of the post, with a vertical slit and piece of board, Q, or metal nailed on top to prevent the access of rain, &c. This modification is always adopted when the post is too small to allow a side slit.

What I claim as my invention, and desire to secure by Letters Patent, is—

Casting the glass insulators of magnetic telegraph and other wires of a cylindrical form, with a flange at one end eccentric with the periphery of the same, its upper part being even with the top, and its lower part dropped slightly below the cylinder, and forming the bore of the cylinder, likewise eccentric with the periphery, so as to allow a greater body of glass to form at its lower part than at its upper part, where it is slit from its outer to its inner periphery to allow the insertion of the wire, and inserting the insulator so formed into a horizontal hole into which the wire is previously introduced through a slit at its side bored through the post, or through a bracket secured on its side or to a tree, and corresponding with the form of the flange which fits therein, in such a manner as to insulate the wire from contact with the post, and prevent the glass from slipping round, and consequently the escape of the wire from the glass, as herein described, or in any other form substantially the same as the form and modifications above described.

JOHN YANDELL.
